COMBINED SHELF AND ILLUMINABLE PICTURE FRAME

Arturo H. Palomares, Compton, Calif.

Substituted for abandoned design application Serial No. 41,849, June 11, 1956. This application August 19, 1957, Serial No. 47,591

Term of patent 3½ years

(Cl. D29—20)

FIG. 1

FIG. 2.

The dominant features of the design reside in the portion shown in full lines. The back of the article is substantially plain and flat.

This application is a substitution for my prior application Serial No. D. 41,849, which is abandoned.

I claim:

The ornamental design for a combined shelf and illuminable picture frame, as shown and described.
